[57] CLAIM

The ornamental design for a brush, as shown and described.

DESCRIPTION

FIG. 1 is a side elevational view of a brush showing my new design;

FIG. 2 is a top plan view thereof;

FIG. 3 is a bottom plan view thereof;

FIG. 4 is a side elevational view of a second embodiment of the design shown in FIG. 1;

FIG. 5 is a top plan view thereof;

FIG. 6 is a bottom plan view thereof.

The undisclosed sides are the same in appearance as the sides shown. The bristles are partially shown for ease of illustration only.

FIG. 1

FIG. 2
